NOISEMAKER FOR BICYCLES

Gordon J. Stepanek, 8023A Lyons St., Niles, Ill.

Filed Feb. 26, 1965, Ser. No. 83,987

Term of patent 7 years

(Cl. D90—1)

FIGURE 1 is a perspective view of a noisemaker for bicycles according to the invention;

FIGURE 2 is a side elevational view of the noisemaker of FIGURE 1; and

FIGURE 3 is a top plan view of the noisemaker of FIGURE 1.

The dominant features of my design reside in the portions shown in full lines.

I claim:

The ornamental design for a noisemaker for bicycles, as shown and described.
